UNITED STATES PATENT OFFICE.

WILLIAM A. RAY AND REX B. BEISEL, OF HEMPSTEAD, NEW YORK, ASSIGNEES TO
CURTISS AEROPLANE & MOTOR CO., INC., A CORPORATION OF NEW YORK.

AEROPLANE LANDING GEAR.

Application filed February 14, 1925. Serial No. 9,106.

To all whom it may concern:

Be it known that we, WILLIAM A. RAY and REX B. BEISEL, citizens of the United States of America, residing at Hempstead, 5 in the county of Nassau and State of New York, have invented certain new and useful Improvements in Aeroplane Landing Gears, of which the following is a specification.

Our invention relates to arresting gears 10 for aeroplanes and is concerned more particularly with an arresting gear attachment for aeroplane landing gears.

In arresting the speed of an aeroplane in landing, and especially where a ship deck 15 landing is made, it is the common practice to hook-in, as it were, the devices carried by the landing gear with a cooperating part of the arresting gear installed on the deck of the ship. Such arresting gear usually includes a series of flexible lines or runners 20 spaced along the ship's deck and with which the devices carried by the aeroplane landing gear are adapted to frictionally engage; such engagement arresting the forward 25 speed of the aeroplane and at the same time holding it (the aeroplane) down on the deck of the ship.

Invariably, in so far as we are aware, 30 the hook-in devices heretofore used have been hung from and fastened to the landing gear axle; such axle forming the permanent part of the landing gear structure and affording a cross-connection between the landing gear wheels. In scout or reconnaissance 35 type craft such an arrangement is preferable, as in craft of this particular type the landing gear axle affords an admirable support for the several hook-in devices. In torpedo carrying craft and in bomb dropping 40 craft, however, a somewhat different condition exists. Such craft are designed to carry a relatively large projectile. Preferably, the projectile is carried beneath and close up under the fuselage or body of the machine at or near its center of gravity. Such projectile, when released, falls away from the aeroplane, and must, if launched with accuracy and precision, leave the machine free from all interference. Accordingly 45 therefore, a landing gear having a cross-axle or cross-connection between its wheels cannot be employed on a bomb carrying or torpedo carrying machine.

In eliminating the cross-connection between the landing gear wheels, we eliminate

at the same time, the structure heretofore used as a support for the hook-in device. The problem, therefore, is to so modify the landing gear of a bombing or torpedo carrying aeroplane as to provide for the attachment of the hook-in device without obstructing the necessary free space required to be provided between the landing gear wheels. The object of the present invention is to meet this problem with as little modification 60 of the arresting gear now used as is possible. The only change required to be made in the landing gear structure is a minor one. Instead of providing closed end hollow axle members, the ends thereof are left open; 65 such open end axle members admitting of a quick attachment and detachment of suitable supports from which the hook-in devices are suspended. Where bombing or torpedo carrying work is required to be performed, the support for said devices is made 70 sectional, each axle member supporting an individual section, and the sections themselves being so proportioned as to leave the required free space between the wheels and 75 beneath the fuselage or body.

Other objects of the invention will be hereinafter set forth.

In the drawings, wherein like reference characters denote like or corresponding 80 parts,

Fig. 1 is a front elevation of an aeroplane landing gear equipped with an arresting gear adjustment particularly suited to the bomb carrying or torpedo carrying machine; 85

Fig. 2 is a similar view of a modified form of arresting gear attachment; such modification being useable with good results where it is intended that the machine be operated 90 as a scout or reconnaissance type craft only, 95 and

Fig. 3 is a detail sectional view of one of the axle members.

In Fig. 1 of the drawings, the fuselage or body of the aeroplane is designated as 100 10, whereas the wings or supporting surfaces thereof are designated as 11—11 respectively. The aeroplane landing gear preferably comprises laterally spaced landing gear wheels 12—12 independently supported, the arrangement of the wheels being such that an open free space is provided between them. Said wheels are supported by means of struts 13—13 and 105 14—14, the latter struts having associated 110

with them suitable shock absorbing mechanism designated as 15—15. The struts 13—13 diverge downwardly from the fuselage or body 10, each strut at its lower end having formed thereon or fastened thereto a hollow axle member 16. The axle member 16 (see Fig. 3) is open ended, and within the hollow of each a support 17 in the form of a transverse arm, is adapted to be inserted or extended. The supports 17, one for each axle member, are held in place by pins 18, the ends of said supports projecting laterally out for some little distance beyond the opposite faces of the landing gear wheels and consequently the opposite ends of the hollow axle members. From the projecting portions of the supports 17 a plural number of hook-in devices 19 of more or less conventional form are suspended. In the form of the invention of Fig. 1, the desired open space between the landing gear wheels is retained and at the same time a sufficient number of hook-in devices 19 are employed to arrest the forward speed of the aeroplane in a landing operation, the arresting action, of course, being obtained thru the co-operation of said devices with that part or portion of the arresting gear (not shown) mounted on the deck of the vessel. Such an arrangement, as intimated, is especially adapted to bomb carrying or torpedo carrying craft wherein the projectile to be launched is supported during flight near the center of gravity and close up under the fuselage or body of the machine.

In the embodiment of the invention illustrated in Fig. 2, the construction of the landing gear is identical with that described in connection with Fig. 1. Instead, however, of providing individual supports 17 for the hook-in devices 19, a support 20 common to the total number of hook-in devices 21 is provided. Said support 20 is carried across the open space above referred to and is preferably in the form of a telescoping rod or tube, the ends of which are pivotally fastened as at 22 to anchorages 23 extended thru the hollow axle members and fastened therein by lock-nuts 24. Such an arrangement can be used to advantage during the operation of the machine for scout or reconnaissance purposes and at the same time admits of the conventional disposition of the hook-in devices, i. e., wholly between the wheels of the landing gear, notwithstanding the fact that the wheels are adapted to yield independently and no cross-connection therebetween, such as an axle, is provided. By making the support 20 sectional and extending one of

the support sections telescopically within the other, the desired independent yielding action of the wheels 12 is made possible.

While we have described our invention in detail in its present preferred embodiment, it will be obvious to those skilled in the art after understanding our invention that various changes and modifications may be made therein without departing from the spirit or scope thereof. We aim in the appended claims to cover all such modifications and changes.

What we claim is:

1. The combination with an aeroplane landing gear including laterally spaced axle members, of an arresting gear therefor comprising a part detachably fastened to said axle members, and devices engageable, in landing the aeroplane, with a cooperating portion of the arresting gear, the devices collectively being carried by that part of the landing gear detachably fastened to said axle members.

2. The combination with an aeroplane landing gear including laterally spaced hollow axle members, of an arresting gear therefor comprising a part detachably fastened to said axle members and extended into the hollowed portions thereof, and devices engageable, in landing the aeroplane, with a cooperating portion of the arresting gear, the devices collectively being carried by that part of the arresting gear detachably fastened to said axle members.

3. The combination with an aeroplane landing gear including laterally spaced axle members, of an arresting gear therefor comprising a divided support having its sections removably fastened respectively to said axle members, and devices engageable in landing the aeroplane, with a cooperating part of the arresting gear, said devices being carried by and movable with said support.

4. The combination with an aeroplane landing gear including laterally spaced hollow axle members, of an arresting gear therefor comprising a divided support detachably fastened to and having its sections extended into the respective hollow axle members, and devices engageable, in landing the aeroplane, with a cooperating part of the arresting gear, said devices being carried by and movable with said support.

In testimony whereof we hereunto affix our signatures.

WILLIAM A. RAY.
REX B. BEISEL.
